HOLDER FOR SEWING IMPLEMENTS

Dennis Arthur Smith, Blytheville, Ark.

Application October 7, 1954, Serial No. 32,581

Term of patent 14 years

(Cl. D3—19)

To all whom it may concern:

Be it known that I, Dennis Arthur Smith, a citizen of the United States and a resident of Blytheville, county of Mississippi and State of Arkansas, have invented a new and original and ornamental Design for a Holder for Sewing Implements, of which the following is a specification, reference being had to the accompanying drawing, forming a part hereof.

Fig. 1 is a side elevational view of a holder for sewing implements showing my new design;

Fig. 2 is a front elevational view; and
Fig. 3 is a top plan view thereof.

I claim:

The ornamental design for a holder for sewing implements, as shown.
